UNITED STATES PATENT OFFICE.

JAMES M. DIAL, OF BOGART, GEORGIA.

LIQUID-FUEL BURNER.

Application filed March 31, 1925. Serial No. 19,662.

To all whom it may concern:

Be it known that I, JAMES M. DIAL, a citizen of the United States, residing at Bogart, in the county of Oconee and State of Georgia, have invented certain new and useful Improvements in Liquid-Fuel Burners; and I do hereby declare the following to be a full, clear, and exact description of the invention, such as will enable others skilled 10 in the art to which it appertains to make and use the same.

My present invention relates to oil burning apparatus of the pan and tray type, exemplified by my pending application for 15 U. S. Letters Patent Serial No. 738,180, filed September 17, 1924, upon which the present structure is an improvement. It has for an object the production of burners designed, arranged and adapted for burning crude oil 20 or other hydrocarbons such as kerosene distillates or fuel oils.

This invention has for a further object the construction of burners of the character indicated, for either domestic or industrial 25 uses, capable of easy installation in stoves, ranges or furnaces originally intended for burning coal, wood, coke or other fuels, as well as in stoves and furnaces designed especially to receive these burners.

With the foregoing and other objects in view, the present improvements will now be particularly described and later pointed out by the appended claims.

In the accompanying drawings which 35 form part of this application for Letters Patent, and whereon corresponding numerals indicate like parts in the several views:

Figure 1 is a horizontal sectional view of 40 the walls of a furnace, containing my improved burner shown in plan, together with the necessary supply and overflow pipes, and means for automatically regulating the supply of fuel oil, the latter means also appearing in plan;

Figure 2 is a vertical sectional view 45 through furnace walls, showing an end elevation of burner, and a side elevation of its regulating means;

Figure 3 is a detail view showing in plan 50 a regulating dial for the fuel supply line;

Figure 4 is a relatively enlarged plan view 55 of burner broken away so as to show underlying parts;

Figure 5 is a longitudinal central sectional 55 view through the complete assembly of burner; and

Figure 6 is a transverse sectional view of burner taken on the line 6—6 of Figure 4.

Reference being had to the drawings and 60 numerals thereon, 10 indicates the walls of a furnace in which grate bars (not shown) are ordinarily supported as at 11. In place of grate bars metal plates of sheet or cast iron, or a rectangular plate such as 12 with 65 center opening 13, is supported by the said flanges 11, and to this is securely bolted the flanged ends 14 of the improved burner body 15. The body member 15 is preferably, but not necessarily, of rectangular box-like form 70 and is provided with an underlying drip-pan 16 extending the full length of burner, and centrally positioned, having near one end an outlet 17. Immediately above the drip pan 16 is a burner trough 18 also centrally located and extending the length of burner. This burner trough 18, is provided with an oil inlet 19 at one end, and also with a sliding scraper or cleaner paddle 20, arranged and adapted to traverse the entire 75 length of the burner trough 18, and to be actuated by agency of a push rod 21 projecting from the burner and furnace for purposes that will hereinafter appear.

At both sides of the burner trough 18, 80 resting upon the surrounding flange 22, are corresponding fire baffles 23 and 23 having upwardly converging top surfaces 24 perforated at frequent intervals as at 25, and oppositely disposed downturned flanges 26, 26, 85 gated inwardly at frequent and regular intervals as at 27, for purposes of controlling the flame and heat distribution, and for other purposes as will appear in the description of operation to follow.

Centrally bolted to both end flanges 14, 14, 90 are racks 28, 28, in which rest a surmounting baffle 29 of V-shape, or upwardly diverging form, upon its underside as best shown by Figure 6. This baffle 29, also of suitable 95 heat resisting metal, and of substantially V-shape in cross section, is filled with fire-clay or some other heat radiating material 29a, as shown by Figures 5 and 6, and at both ends is provided with adjusting set screws 100 30, 30, two upon each side, threaded through the said metal base of this baffle element, and at their lowermost ends resting directly upon 105

the upper surfaces of the supporting racks 28, 28, thus providing for accurate adjustment of the said baffle plate in all directions, the better to control the distribution of flame 5 and heat from the burner when in service.

At a convenient location, more or less remote from the burner hereinbefore described, is a fuel supply tank or source of oil supply 31, communicating directly with the supply 10 inlet 19 of burner trough 18, by means of a supply pipe 32, valved as at 33 for regulating the rate of supply, and provided with a dial plate 34 for showing the extent of such feed as will later appear.

15 In the supply pipe 32 there is also a cut-off valve 35 as shown by Figure 2, and up through the said dial plate 34 projects the stem 36 of the supply valve 33 upon the upper end of which latter is rigidly secured 20 a pointer or indicator 37 crossing the dial diametrically and having a depending pin 38 in one end arranged and adapted to spring into one or the other of the holes 39. Opposite each of the holes 39 are numerals 25 1 to 6 inclusive, more or less, which indicate the extent to which the supply valve 33 is opened when pin 38 occupies the opposite hole or indentation 39. A valve-wheel 39' is also fixed to the projecting end of stem 36, 30 as a convenient means of rotating the latter.

Leading from the outlet 17 of drip pan 16 is an overflow pipe 40 terminating in a drip can or container 41. This drip can 41 and its counterweight 42 are mounted upon opposite ends of a tubular actuating lever 43, which in turn is pivotally mounted upon the stem 44 of the shut-off valve 35 aforesaid. The normal position of these parts, being as indicated by full lines in Figure 2, it is obvious that any overflow from the drip-pan 16 will find its way directly into the container 41, to overbalance the weight 42, and, as a result, rotate stem 44, automatically closing the cut-off valve 35, as parts assume 45 the position indicated by dotted lines in Figure 2.

This being a description of the invention in one form of embodiment, its use and operation will now be briefly set forth as follows:

Presuming that my improved burner, with supply tank and intermediate connections, has been installed in a furnace substantially as indicated by Figures 1 and 2 of the drawings, the liquid fuel is then permitted to flow from tank 31 through valve 33 and supply pipe 32 to burner trough 18 where it is ignited and burns. Air then entering the burner from below upon both sides of drip-pan 16, is first deflected by upwardly converging baffles 23 and 23, and is then turned down by their inner flanges 26, 26, through a number of gates or ports 27 which cause a multiplicity of independent streams. This 60 circuitous course of travel also retards the

air supply somewhat and insures a thorough commingling thereof with the flame which it supports because of the said retarded circuitous manner of delivery through the independent ports 27 in a multiplicity of independent streams. Moreover, it will be noted that the openings 25 through the baffles 23, 23, permit the escape of a limited amount of air over the surfaces of these baffle elements, and serves to lift the flame 75 out of actual contact with the upper surfaces thereof, thus rendering the said baffles much more durable, greatly increasing efficiency of the burner as a whole, and serving also as a muffler to reduce the roaring sounds 80 common to oil burners of this type.

In its further passage upward the flame then impinges upon the under diverging surfaces of the final deflector 29, 29, which, together with its within contained heat radiating material 29^a, becomes incandescent 85 and contributes materially to the burner efficiency.

In order to insure a uniform distribution 90 of heat at both sides and at both ends of the burner the said final deflector 29 is adjustable in all directions by agency of the several screws 30 bearing upon their supporting racks 28.

In the event that oil or other liquid fuel 95 is supplied to burner 18 too rapidly the supply is automatically cut off as follows: The overflow from said burner falls into the drip-pan 16, and upon reaching the level of outlet 17, passes through outlet pipe 40 to the container 41 until the latter is overbalanced, lifting its counterweight 42 to the position indicated by dotted lines, whereby the cut-off valve 35 in supply line 32 is automatically closed, and remains closed until 100 parts are manually returned to their normal operative positions.

In opening the main supply valve 33, more or less according to requirements imposed upon the burner, hand wheel 39' is 105 rotated in the usual manner, and with it moves the indicator 37 until its stop-pin 38 is permitted to spring into the appropriate hole or depression 39, at which time the opposite end of pointer 37 will show upon the face of dial 34 the extent to which valve 33 is open, this being indicated by the raised numerals shown upon the edge of said dial in Figures 1 and 3 of the drawings.

Having thus described my present invention what I now claim and desire to secure by Letters Patent is:

1. A liquid fuel burner including in combination a burner body, a burner trough supported within said body, means for supplying liquid fuel to the burner trough, a baffle plate upon each side of said burner trough arranged and adapted to direct an air supply into the path of the products of combustion, and ports in the opposing sides 125 130

of said baffle plates for delivering the air supply in a multiplicity of independent streams.

2. A liquid fuel burner including in combination, a burner body, a burner trough supported within said body, means for supplying liquid fuel to the burner trough, a perforated baffle plate upon each side of said burner trough arranged and adapted 10 to direct an air supply into the path of the products of combustion, and ports in the opposing sides of said baffle plates for delivering the air supply in a multiplicity of independent streams.
- 15 3. A liquid fuel burner including in combination a burner body, a burner trough supported within said body, means for supplying liquid fuel to the burner trough, a perforated baffle plate upon each side of 20 said burner trough arranged and adapted to direct an air supply into the path of the products of combustion, and ports in the opposing downturned angular sides of said baffle plates for delivering the air supply in 25 a multiplicity of independent streams.

4. A liquid fuel burner including in combination a burner body, a burner trough supported within said body, means for supplying liquid fuel to the burner trough, a baffle plate upon each side of said burner trough arranged and adapted to direct an air supply into the path of the products of combustion, ports in the inner downturned edges of said baffle plates for delivering the 30 air supply in a multiplicity of independent streams, and a centrally positioned diverging flame deflector surmounting the burner.

5. A liquid fuel burner including in combination, a burner tray, means for supplying liquid fuel to said tray, a flame deflector surmounting the burner tray, and means for 35 tilting the said deflector in all directions.

6. A liquid fuel burner including in combination, a burner tray, means for supplying liquid fuel to said tray, a flame deflector 40

surmounting the burner tray, a deflector supporting rack at ends of the burner tray, and set-screws interposed between said rack and deflector whereby the latter may be tilted in all directions.

50 7. A liquid fuel burner including in combination a burner tray, means for supplying liquid fuel to said tray in predetermined quantities, and a scraper-blade fitted to the interior of the burner tray said scraper-blade having an actuating rod projecting from the burner by which it may be caused to traverse the entire length of said tray.

8. A liquid fuel burner including in combination a burner body, a burner trough supported within said body, means for supplying liquid fuel to the burner trough, a baffle plate upon each side of said burner trough arranged and adapted to direct an air supply into the path of the products of combustion, oppositely disposed ports through the inner downturned edges 60 of said baffle plates for delivering the air supply in a multiplicity of independent streams, and a centrally positioned drip pan 65 beneath the burner trough.

9. A liquid fuel burner including in combination a burner body, a burner trough supported within said body, means for supplying liquid fuel to the burner trough, a baffle plate upon each side of said burner trough arranged and adapted to direct an air supply into the path of the products of combustion, oppositely disposed ports through the inner downturned edges of said 70 baffle plates for delivering the air supply in a multiplicity of independent streams, a centrally positioned drip pan beneath the burner trough, an overflow pipe from the latter, and means under control of said overflow for closing a cut-off valve in the supply pipe line.

In testimony whereof I affix my signature.

JAMES M. DIAL.
